UNITED STATES PATENT OFFICE.

GEORGE F. MOOREHEAD, OF DES MOINES, IOWA, ASSIGNOR OF ONE-HALF TO ARTHUR C. WRIGHT, OF DES MOINES, IOWA.

REFRIGERATOR SHOW-CASE.

1,309,151.

Specification of Letters Patent.

Patented July 8, 1919.

Application filed February 27, 1917. Serial No. 151,182.

To all whom it may concern:

Be it known that I, GEORGE F. MOOREHEAD, citizen of the United States of America, and resident of Des Moines, Polk county, Iowa, have invented a new and useful Refrigerator Show-Case, of which the following is a specification.

The object of this invention is to provide an improved construction for a refrigerator show-case in which a forced draft is employed to maintain a constant current of air over the refrigerating means and through the display compartment.

A further object of this invention is to provide an improved construction for a refrigerator show-case in which the entire upper portion of the device may be utilized as a display compartment or provision chamber.

20 A further object of this invention is to provide an improved and efficient arrangement of the draft-creating means and the refrigerating means.

25 A further object of this invention is to provide for ready access to all parts of the display compartment without undue effort or bending.

30 A further object of this invention is to provide for a very low temperature coupled with economy in ice consumption, where ice is used as the refrigerating means.

35 A further object of this invention is to provide a thorough and positive circulation which is capable of being regulated to meet varying conditions.

40 My invention consists in the construction, arrangement and combination of elements hereinafter set forth, pointed out in my claims and illustrated by the accompanying drawing, in which—

Figure 1 is an end elevation of my improved show-case. Fig. 2 is a transverse vertical section on the indicated line 2—2 of Fig. 3. Fig. 3 is a central, vertical longitudinal section of the complete device.

45 In the construction of the device as shown a show-case housing is formed of a bottom 10, front 11, rear wall 12, ends 13, and top 14, preferably formed of wood except as otherwise indicated. The greater portion of the

5 top 14, as well as the upper portions of the ends 13 and front wall 11 are glazed to permit viewing of the contents of the display compartment. The upper portion of the rear wall 12 preferably is inclined forwardly 55 at an angle and the greater portion thereof is formed of a plurality of glazed sliding doors 15, to permit convenient access to the rear of the display compartment. A horizontal partition 16 is mounted in the show-case housing and provides a floor or bottom for the upper display or provision compartment, said partition being located below the doors 15 and inclined portion of the rear wall 12 and also below the glazed portions 60 of the front wall 11 and ends 13. The partition 16 may be formed of any suitable material but preferably is composed of or faced with a marble slab to provide a sanitary and easily cleaned support for provisions to be 65 displayed in the case. The partition 16 is formed with openings 17, 18 at its ends, preferably extending entirely across the case, and gratings or screens 19 are removably mounted in said openings. Vertical partitions 20, 21 are mounted in and transversely of the lower portion of the case, below the horizontal partition 16, and divide the lower part into three substantially equal compartments, indicated by the numerals 22, 23, 24 70 respectively. The central compartment 23 is the refrigerating compartment and is adapted to contain the refrigerating means, and to this end a skeleton rack or false bottom 25 is mounted, preferably removably, in the lower part of said compartment and may 75 be composed of slats spaced apart and supported at their ends by the walls of the compartment. A quantity of ice 26 may be mounted loosely on the rack 25 and may be 80 renewed from time to time as indicated; or any mechanical refrigerating means such as coils may be employed in the same location, in a common manner. A fan housing 27 is mounted in the compartment 22 adjacent the 85 partition 20 and extends transversely of the bottom of said compartment and is adapted to contain a motor driven fan 28 adapted to receive current through a conductor 29. The fan housing 27 is formed with a removable 90

95

100

top 30 spaced below the horizontal partition 16, and is also formed with a circular opening 31 corresponding approximately to the diameter of the fan and leading to the compartment 22. The partition 20 is foreshortened or cut away at its bottom throughout its entire length, whereby a long narrow opening 32 is provided leading from the refrigeration compartment 23 to the fan housing 27, and said opening is entirely below the level of the top of the rack 25, and below the refrigerating means 26. The partition 21 is imperforate in its lower portion, to a level with the top of the rack 25, and is of open or skeleton construction above said rack, being formed of a number of spaced slats 33 set crosswise but inclined downwardly somewhat toward the refrigerating chamber 23 and the refrigerating medium 20 therein on the rack 25.

In practical operation merchandise to be displayed, such as fresh meats, vegetables and the like, are placed on the horizontal partition 16, the gratings 19, or major parts 25 thereof, being left unobstructed. The fan 28 is operated to force currents of air, drawn from the refrigerating compartment 23 through the opening 32 to the fan housing 27, through the opening 31, to the end of the compartment 22 and upwardly through the screened opening 17, thence traversing the display compartment from end to end and passing downwardly through the screened opening 18 to the compartment 24 and 30 through the skeleton portion of the partition 21 to the refrigerating compartment 23 once more, the direction and course of said currents being indicated by the arrows in Fig. 3. The currents of air are forced to descend 35 in the refrigerating chamber 23 in order to find an outlet, as the partition 20 is imperforate above the rack 25, whereby said currents are forced to pass downwardly around the refrigerating medium 26 and through 40 said rack, and are cooled by contact with said refrigerating medium, thence passing outwardly through the opening 32 as before. Thus a constant current or circulation of air is maintained by the fan 28, passing up- 45 wardly to and then through the display compartment, and downwardly to the compartment 24, then to the refrigerating compartment and down and around the refrigerating medium and to the fan compartment. Thus 50 effective cooling of the air currents is obtained and results in effective cooling of the contents of the display case, a low temperature being maintained at small cost. The circulation is positive, owing to the location 55 of the fan, and it may be regulated by regulating and adjusting the variable speed control of the fan in a common manner.

As the refrigerating medium and the forced draft means are located in the lower

compartment of the case, the entire upper 65 portion may be employed for display of goods. The compartments 22, 24 may be employed in part for storage, care being taken not to fill them so completely as to interfere with the circulation through said compartments. 70

Hinged doors (not shown) are provided in the rear wall for access to the compartments 22, 23, 24, one door preferably being provided for each of said compartments. 75

The capacity of the fan is equalized to the capacity of the apertures through which the currents pass, so that when the doors 15 of the display compartment are opened there is no draft of warm air inwardly nor of cold 80 air outwardly, for the forced current established precludes the possibility of lateral currents. 85

I claim as my invention—

1. A refrigerator show-case, comprising a 85 housing formed with a horizontal partition forming the bottom of a display case, said partition being formed with spaced openings at its ends only, the intermediate portion of said partition being imperforate, vertical 90 partitions below said horizontal partition dividing the lower part of said housing into end compartments and an intermediate refrigerating compartment located entirely beneath said display case, a skeleton rack 95 mounted in the refrigerating compartment and adapted to carry a refrigerating medium, one of said vertical partitions being formed with an opening at its base below the level of said rack, and a blower device located adjacent the last-named opening, the other vertical partition being formed with openings above the level of the skeleton rack, whereby air is drawn from said refrigerating compartment and is forced upwardly into and 100 from end to end of said display case and is then returned to said refrigerating compartment. 105

2. A refrigerator show-case, comprising a 110 housing formed with a horizontal partition, the entire upper portion of said housing above said partition being formed as a display case, said partition being formed with screened openings at its ends only, the intermediate portion of said partition being imperforate, vertical partitions below said horizontal partition dividing the lower part of said housing into end compartments communicating with the upper part thereof through said screened openings and an intermediate refrigerating compartment, a skeleton rack mounted in said refrigerating compartment and adapted to carry a refrigerating medium, one of said vertical partitions being formed with an opening at its base 115 below the plane of the skeleton rack, a fan housing in one end compartment communicating with the last-named opening and 120

- formed with an exit opening, and a fan mounted in said fan housing between the openings thereof, the other vertical partition being formed with a series of openings above 5 the plane of the skeleton rack, whereby air is drawn from said refrigerating compartment through said fan housing and is forced up- wardly into and from end to end of said display case and is then returned to said refrigerating compartment through the last 10 named openings.

Signed by me at Des Moines, Iowa, this 21st day of February, 1917.

GEORGE F. MOOREHEAD.
